UNITED STATES PATENT OFFICE

EDWARD D. PERRY, OF WATERTOWN, CONNECTICUT, AND GEORGE E. BALL, OF CRANSTON, RHODE ISLAND, ASSIGNORS TO THE BEARDSLEY & WOLCOTT MANUFACTURING COMPANY, OF WATERBURY, CONNECTICUT, A CORPORATION OF CONNECTICUT

DESIGN FOR A SADIRON

Application filed October 13, 1932. Serial No. 45,326. Term of patent 7 years.

To all whom it may concern:

Be it known that we, EDWARD D. PERRY and GEORGE E. BALL, citizens of the United States, residing at Watertown and Cranston, in the counties of Litchfield and Providence, and States of Connecticut and Rhode Island, respectively, have invented a new, original, and ornamental Design for Sadirons, of which the following is a specification, reference being had to the accompanying drawing, forming part thereof,

Fig. 1 is a perspective view of the sadiron, showing our new design,

Fig. 2 is a side elevational view of the same.

We claim:

The ornamental design for a sadiron as shown.

In testimony whereof, we have affixed our signatures to this specification.

EDWARD D. PERRY,
GEORGE E. BALL.
